UNITED STATES PATENT OFFICE.

EDWARD KEEFE, OF JERSEY CITY, NEW JERSEY.

BACKING-UP DISTRIBUTER.

1,185,410.

Specification of Letters Patent.

Patented May 30, 1916.

Application filed December 19, 1914, Serial No. 878,107. Renewed April 20, 1916. Serial No. 92,530.

To all whom it may concern:

Be it known that I, EDWARD KEEFE, a citizen of the United States, and a resident of Jersey City, in the county of Hudson and 5 State of New Jersey, have invented certain new and useful Improvements in Backing-Up Distributers, of which the following is a specification.

My invention relates to electrotyping, and 10 the main object thereof is to provide means for uniformly distributing the molten metal forming the back of an electrotype; a further object is to provide means for straining the molten metal as it is poured over the 15 copper shell to form a support therefor; a further object is to provide such a device which is entirely independent of the electrotype and of the tray wherein it is placed for backing-up, thereby enabling an opera- 20 tor to place the same at any position in the tray; and further objects are to provide such devices which are simple in construction and use, well adapted for the purpose for which they are designed, and comparatively inex- 25 pensive.

My invention is fully described in the following specification, of which the accompanying drawings form a part, in which like reference characters are used to designate 30 like parts in each of the views, and in which:—

Figure 1 is a top plan view of my invention; Fig. 2 is a side elevation thereof, partly in section on the line 2—2 of Fig. 1; Fig. 3 35 is a section taken on the line 3—3 of Fig. 2, and showing, also, the tray and electrotype shell; and Fig. 4 is a plan view, on a reduced scale, showing one position of the distributor with respect to the trap and elec- 40 trotype shell.

Electrotype shells are now usually backed up by being placed in a tray and molten metal poured over the back thereof, directly onto the said shell, or shells when more than 45 one are arranged in the same tray, but this causes the molten metal to flow unevenly and sometimes results in injury to the electrotype shell. By means of my method, however, I pour the molten metal through 50 my distributor, which consists of a frame 5 having a horizontal partition 6 arranged therein at a point intermediate the height thereof, approximately central as shown, and perforated as shown at 7 to permit the 55 passage of the molten metal therethrough,

but preventing the passage of foreign or deleterious matter, thereby insuring the deposit of clean metal on the electrotype shell or shells 8.

The frame 5 is provided with handles 9 whereby the device may be placed in position and removed therefrom, and the lower edges of said frame are provided with a plurality of spaced, segmental, notches 10 therethrough, forming passages of restricted 60 cross-sectional area for the molten metal; the molten metal is, therefore, divided into a multiplicity of streams of restricted volume, thus insuring an equal distribution of the same over the electrotype shell and preventing injury thereto now occasioned by the direct impact of the main stream of metal from the pot 11.

A further, and highly important, function of my device is to utilize the same as a 70 weight for maintaining the electrotype shell in contact with the planetary bottom of the tray 12, and I may use either one or several of the distributor for each cast or, when only one is used, I may move the same to 75 different positions for the cast, this use not being obligatory upon me, however, nor any other method of use, the main function being to break up the stream from the melting-pot into a plurality of streams over the 80 entire area of the bottom of my distributor, and another function being to insure a clean 85 metal for the backing-up of the shell.

My invention is very simple, though of great value in the art referred to, and, while 90 I have described the same as used for backing-up electrotypes, it may also be used for casting stereotypes; further, while I have shown a present preferred form of embodiment of my invention, it will be understood 95 that I do not desire to limit myself to any specific details, as many changes thereover may be made, within the scope of the following claims, without departing from the spirit of my invention, or sacrificing its ad- 100 vantages.

Having fully described my invention, what I claim as new, and desire to secure by Letters Patent, is:—

1. A device of the class described, comprising a frame having a horizontal partition therein provided with vertical perforations therethrough, and having a plurality of restricted passages at the lower edge thereof for the molten metal. 105

2. A device of the class described, comprising a frame having a plurality of spaced, segmental, notches along the lower edge thereof, forming restricted passages for the 5 molten metal to distribute the same uniformly over a desired surface.
3. A device of the class described, comprising a frame having a handle on the upper surface thereof, a perforated, horizontal, 10 tall, partition therein, intermediate the height

thereof, and having a plurality of spaced notches along the bottom edge thereof.

In testimony whereof I have signed my name to this specification in the presence of two subscribing witnesses.

EDWARD KEEFE.
